UNITED STATES PATENT OFFICE.

HERMAN G. PAPE, OF NEW YORK, N. Y., ASSIGNOR, BY MESNE ASSIGNMENTS, TO BEAVER MACHINE AND TOOL CO., INC., OF NEWARK, NEW JERSEY, A CORPORATION OF NEW JERSEY.

DOUBLE-THROW QUICK-MAKE AND QUICK-BREAK SWITCH.

Application filed January 14, 1919. Serial No. 271,129.

To all whom it may concern:

Be it known that I, HERMAN G. PAPE, of New York, in the county and State of New York, have invented a new and useful 5 Double-Throw Quick-Make and Quick-Break Switch, of which the following is a specification.

One feature of my invention is a double throw switch having a quick make and 10 quick break action in throwing the switch into and out of engagement with either one of two circuits as desired.

Another feature is such a switch having means to prevent the making of both of 15 said circuits at the same time.

Another feature is providing such a switch with control members and with means which operate the movable contacts independently of the control members.

20 Another feature is a direct connection between said control members to prevent the making of said circuits at the same time.

Other features will be pointed out below.

In the drawings—

Figure 1 is an elevation of a double throw switch showing both circuits open;

Figure 2 is a plan of the same;

30 Figure 3 is an elevation of the same but showing one circuit closed;

Figure 4 is a fragmentary section described below;

Figure 5 is a section on line 5—5 of Figure 4;

Figure 6 is a detail of the cross-bar described below;

Figure 7 is a plan of a modified form described below; and

40 Figure 8 is an elevation of the same; and

Figure 9 is a detail of one of the switch blades.

Base A is made of slate or other suitable material. I illustrate a double pole switch attached to said base although my invention contemplates a single pole or three pole or any other desired form.

50 Suitably fixed to the base are two forked brackets B and B' having stop lugs b and b' for a purpose hereinafter described. Upon these brackets are pivotally mounted the control members for the switch members. Each control member includes two

side members, a cross-member and a handle 55 and description of one will now be made. The control member at the left in Figure 2 comprises side member d pivoted to bracket B by screw E and side member d' pivoted to bracket B' by screw E'. These 60 side members d and d' are connected as by screws d² to cross-member D which is of insulating material and to which is suitably secured operating handle D', although my switch may be controlled otherwise than by hand. I provide a guard D² of insulating material at the base of the handle to protect the hand of the user against the moving blades described below.

Metal plate F carries a binding screw f 70 for connection to a wire leading to a main circuit and said plate is electrically connected to a metal bracket having two arms f² and f³ which form a pivotal bearing for the inner ends of contact blades G and G', 75 suitable washers f⁴ and f⁵ being provided and the parts held in pivotal engagement by rivet f⁶ or otherwise. Blades G² and G³ are similarly pivoted. Blades G and G² are rigidly connected to cross-bar G⁴ of 80 insulating material so that when said bar moves blades G and G² move in unison. Said bar G⁴ is made in two pieces which are suitably recessed to receive and hold blades G and G², said pieces being held 85 together by screws such as g. To cross-bar G⁴ is connected plate G⁵ by screws G⁶ or otherwise, said plate having an extension G⁷ with a perforation through which is hooked one end of coiled spring G⁸, which 90 spring extends through a suitable opening in side member d and through a similar opening in the adjacent side member h of the other control member. The other end of said spring is hooked through a perforation in a projecting portion d³ of side member d.

Screw K holds plate K' and fixed terminal clip contact K² to the base, the plate K' carrying binding post k for electrical 100 connection with a desired circuit, contact K² cooperating with blade G. I similarly provide fixed contact terminal K³ to cooperate with blade G².

Assuming the device to be in the position shown in Figure 1 and that it is desired to make a circuit through terminal contacts K² and K³ the handle D' will be 105

raised and the point of connection of the spring G^8 with portion d^3 will be carried to the line extending from screw E to the point of connection of the spring with portion G^7 compressing the spring and when said line is passed the spring acts to swing the blades G and G^2 with a quick snap action into engagement with contacts K^2 and K^3 , it being understood that spring G^9 which has similar connection with cross-bar G^4 and side piece d' takes part in this quick make. Reversal of the movement of the handle will cause disengagement of blades G and G^2 from the contacts K^2 and K^3 with a snap action which gives a quick break.

Similarly handle H is connected by side pieces h and h' , springs h^2 and h^3 and cross-bar h^4 to blades G' and G^3 which are operated to quickly make and quickly break contact with fixed terminal clip contacts H' and H^2 , each electrically connected with binding posts which may be electrically connected with another desired circuit, the closed circuit position for blades G' and G^3 being shown at the right of Figure 3.

It will be understood that the side members d , d' , h and h' have suitable apertures to permit free movement of the springs and that while the handle members are controlling members yet when in moving the handle the line above described is passed in either direction then the spring actually operates the blades with a quick movement in either direction independently of the handle.

If the circuit at one side is open then the circuit at the other side may be opened or closed as desired but if the circuit is closed at one side as at the right in Figure 3 then the circuit at the other side can not be closed until the circuit at said right side is opened so that it is impossible to have the circuits made at both sides at the same time and I shall now describe a mechanism for accomplishing this result. I provide lug M on side piece d and if handle D' is moved upwardly in Figure 3 said lug engages the periphery of side piece h at about the point x at which point said periphery extends outwardly from pivot E further than it does opposite said lug. This engagement carries side piece h around as handle D' is raised with the result that handle H is lowered and the blades G' and G^3 disengage from contacts H' and H^2 , said blades being swung by springs h^2 and h^3 into the open position of Figure 1, handle D' continuing its upward movement to make the circuit at its side of the device. I provide a similar lug for side piece d' to engage the periphery of side piece h' . In the same way I provide a lug M' on side piece h to engage the periphery of side piece d and a similar lug on side piece h' to engage the periphery of side piece d' .

Plate F' is similar to plate F and is adapted to be electrically connected to the same main circuit to which plate F and binding post f are connected.

Hooks N and N' are suitably connected to the base and limit the upward movement of cross-bar G^4 while similar hooks N^2 and N^3 limit the upward movement of cross-bar H^4 . Downward movement of cross-bar G^4 is limited by spring arms P and P' at one side these arms being held beneath plates F and F' by screws (one being shown at F^2) and extending integrally to form spring arms P^2 and P^3 which limit the downward movement of cross-bar h^4 .

Movement of that control member which is at the right in Figure 1 in a downward direction is limited by the lug M' on side member h engaging lug b' on bracket B and by a similar engagement of the lug on side member h' with a lug on bracket B' and movement in the other direction is limited by engagement of the side member itself with the lug M on side member d at about the point x and by a similar lug on side member d' engaging side member h' . Movement of the other control member is similarly limited in both directions.

In Figures 7, 8 and 9 I show a modification in which handle R , guard R' , cross-member R^2 , side pieces r and r' and springs R^3 and R^4 are similar to the corresponding elements in the other form described above. The brackets R^5 and R^6 , the plates R^7 and R^8 adapted to be electrically connected to a main circuit, the fixed contact terminals R^9 and R^{10} of one set and the fixed contact terminals R^{11} and R^{12} of another set being similar to the corresponding parts of said other form.

I provide however cross-bars S and S' of insulating material each consisting of two pieces as in the other form, the pieces of bar S being recessed to receive a portion of blades T and T' and being clamped thereto by screws s and s' and the two pieces of bar S' being recessed to receive other portions of blades T and T' and being clamped thereto by screws s^2 and s^3 .

A side plate T^2 has portion t extending beneath the cross-bar S which is connected thereto by one of the screws s and a similar portion t' extending beneath cross-bar S' which is connected thereto by one of the screws s^3 . Said plate has an upward extension perforated to receive the hooked end of spring R^3 . A similar plate T^3 is provided at the other ends of the cross-bars S and S' and is similarly connected to said bars and to spring R^4 .

Blade T is made in one piece and has a contact end t^2 to engage fixed contact R^9 and a contact end t^3 to engage fixed contact R^{11} .

Blade T' is similarly made in one piece

and has a contact end t^4 to engage fixed contact R^{10} and a contact end t^5 to engage fixed contact R^{12} .

- 5 The movements of the side pieces r and r' are limited by their engagement with lugs r^2 and r^3 on bracket R^5 and by similar lugs on bracket R^6 and the movement of the cross-bars are limited by the spring arms r^4 and r^5 as in the other form.
- 10 It will be clear that in this form the current may be thrown to one side of the device or the other as desired with a quick make and quick break snap action the operative connection between the movable switch ends t^2 and t^3 being permanent or fixed and preventing the making of the circuit at both sides of the device at the same time because if the circuit is made, as at the right side of Figure 8, movement of the handle will 15 compress the springs which will then move the blades T and T' shifting the movable contact ends t^2 and t^5 out of engagement with fixed contacts R^{11} and R^{12} before the movable contact ends t^2 and t^5 can engage 20 the fixed contacts R^9 and R^{10} , there being no neutral position in this form.

An important feature is that the insulated cross-bar G^4 , h^4 , S and S' carry the blades into and out of contact in unison which is 25 important because otherwise one blade might make or break contact before the other or others with the result that arcing or sparking might be caused.

It will also be clear that there might be, 30 for example, two circuits each side of the switch and in such case my invention permits making those at one side at one time but would prevent at that time the making of any circuit at the opposite side.

40 What I claim is:

1. A device of the character described comprising two sets of terminal contacts, each set comprising one or more of such contacts; a handle; a switch member adapted 45 to be electrically connected to a main circuit; a spring directly connected to said handle and to said switch member and being put under stress by said handle and when so stressed causing said member to engage either one of said sets of contacts as desired 50 with a quick snap action and to be disengaged from either one of said sets as desired with a quick snap action, the path of movement of said switch member being unobstructed at all times.

2. A device of the character described comprising two sets of terminal contacts, each set comprising one or more of such contacts; a handle; a switch member adapted 55 to be electrically connected to a main circuit; a spring directly connected to said handle and to said switch member and being put under stress by said handle and when so stressed causing said member to engage either one 60 of said sets of contacts as desired with

a quick snap action and to be disengaged from either one of said sets as desired with a quick snap action, the path of movement of said switch member being unobstructed at all times, and means to prevent the engagement of said switch member with more than one of said sets at one time. 70

3. A double throw switch comprising a set of one or more fixed terminal contacts; a switch member adapted to be electrically connected with a main circuit and operable to make and break connection with said set; a second set of one or more fixed terminal contacts; a second switch member adapted to be electrically connected with said main 75 circuit and operable to make and break connection with said second set; said switch members being movable independently but having an operable connection which prevents making of the connection between both 80 of said switch members and their respective sets of contacts at the same time, each switch member being movable independently of the other to break the circuit. 85

4. A double throw switch comprising a 90 set of one or more terminal contacts; a switch member adapted to be electrically connected with a main circuit and operable to make and break connection with said set; a second set of one or more terminal contacts; a second switch member adapted to be electrically connected with said main circuit and operable to make and break connection with said second set; said switch members being 95 movable independently but having operative connection such that movement of one to engage its set will, if the other switch is engaging its set, break the latter engagement before said one switch engages its set, each switch member being 100 movable independently of the other to break the circuit. 105

5. A double throw switch comprising a set of one or more contact terminals; a switch member therefor; a second set of one or more contact terminals; a switch member therefor; each of said switch members being operable to make and break contact with its set of terminals independent of the other switch member when the other switch member is disengaged from its set and said switch members being movable independently but having operative connection which prevents making of the connection between both of said switch members and their respective sets of terminals at the same time. 110 115

6. A device of the character described comprising a set of one or more fixed terminal contacts; a switch member adapted 125 to be electrically connected with a main circuit and operable to make and break connection with said set; a second set of one or more fixed terminal contacts; a second switch member adapted to be electrically 130

- connected with said main circuit and operable to make and break connection with said second set; said switch members having positions of rest when both are disconnected 5 from their respective sets of fixed contacts but having an operative connection which prevents making of the connection between both of said switch members and their respective sets of contacts at the same time, 10 and means to cause each of said switch members to make connection with its set of terminal contacts with a quick snap action and to be disengaged therefrom with a quick snap action. 15 7. A device of the character described comprising a set of one or more terminal contacts; a switch member adapted to be electrically connected with a main circuit; means to operate said member to engage 20 said set with a quick snap action and to be disengaged from said set with a quick snap action; a second set of one or more terminal contacts; a second switch member adapted to be electrically connected with said main 25 circuit; means to operate said second switch member to engage said second set with a quick snap action and to be disengaged from said second set with a quick snap action; said switch members being movable 30 independently but having an operative connection which prevents making of the connection between both of said switch members and their respective sets of contacts at the same time. 35 8. A device of the character described comprising a handle; a set of one or more terminal contacts; a switch member adapted to be electrically connected with a main circuit and controlled by said handle; means 40 to operate said switch member independently of said handle to engage said set of contacts with a quick snap action and to be disengaged from said set with a quick snap action; a second handle; a second set of one 45 or more terminal contacts; a second switch member adapted to be electrically connected with said main circuit and controlled by said second handle; means to operate said second switch member independently of said 50 second handle to engage said second set of contacts with a quick snap action and to be disengaged from said second set of contacts with a quick snap action; said switch members having an operative connection which 55 prevents making of the connection between both of said switch members and their respective sets of contacts at the same time. 60 9. A device of the character described comprising a plurality of terminal contacts; a switch member carrying a plurality of contact members adapted to be electrically connected with a main circuit; means to operate said member to cause 65 said contact members to engage said terminal contacts with a quick snap action and to be disengaged from said terminal contacts with a quick snap action; a second switch member carrying a plurality of contact members adapted to be electrically connected with said main circuit; means to operate said second switch member to cause its contact members to engage said second 70 terminal contacts with a quick snap action and to be disengaged therefrom with a quick snap action; said switch members being movable independently but having an operative connection which prevents making of the connection between the contact members of both switches with their respective contact terminals at the same time. 75 10. A device of the character described comprising a set of one or more terminal contacts; a switch member adapted to be electrically connected with a main circuit; means to operate said member to engage 80 said set with a quick snap action and to disengage it from said set with a quick snap action, said operating means including a pivoted control member; a second set of one or more terminal contacts; a second switch member adapted to be electrically connected with said main circuit; means to operate said second switch member to engage said second set with a quick snap action and to disengage it from said second set with a quick snap action, said last-mentioned operating means including a pivoted 85 control member; said pivoted control members having portions which cooperate to prevent making of the connection between both of said switch members and their respective sets of contacts at the same time. 90 11. A device of the character described comprising a set of one or more fixed terminal contacts; a switch member adapted to be electrically connected with a main circuit; means for controlling said switch member including a cross-member and a pivoted side member supporting said cross-member, said side member having a perforation and a projecting portion and said means including a spring to cause said switch member to engage and be disengaged from said set with a quick snap action; a second set of one or more fixed terminal contracts; a second switch member adapted to be electrically connected with said main circuit; means controlling said second switch member including a cross-member and a pivoted side member supporting said cross-member, said side member having a perforation and a projecting portion and said last-mentioned means including a spring to cause said second switch member to engage and be disengaged from said second set with a quick snap action, said springs extending through said perforations; and the projecting portion of each side member cooperating with the other side. 100 115 120 125 130

member to prevent the making at the same time of the connection between both of said switch members and their respective sets of contacts.

5 12. A device of the character described comprising a set of one or more fixed terminal contacts; a switch member adapted to be electrically connected with a main circuit and operable to make and break connections with said set with a quick snap action; means independent of said contacts to limit the movement of said switch member in both directions; a second set of one or more fixed terminal contacts; a second switch member adapted to be electrically connected with said main circuit and operable to make and break connection with said second set with a quick snap action; and means independent of said contacts to 10 limit the movement of said second switch member in both directions; said switch members having an operative connection which prevents making of the connection between both of said switch members and 15 their respective sets of contacts at the same time.

13. A double throw switch comprising a handle; movable switch mechanism adapted to be electrically connected with a main circuit and controlled by the handle; means to move said mechanism independently of the handle with a quick snap action into and out of engagement with the fixed contacts of other circuits as desired; and means 20 to prevent any but the desired of said other circuits being made at the same time.

14. A device of the character described comprising a handle; a set of one or more terminal contacts; a switch member adapted to be electrically connected with a main circuit and controlled by said handle; means to operate said switch member independently of said handle to engage said set of contacts with a quick snap action and to be disengaged from said set with a quick snap action; a second handle; a second set of one or more terminal contacts; a second switch member adapted to be electrically connected with said main circuit and controlled by said 25 second handle; means to operate said second switch member independently of said second handle to engage said second set of contacts with a quick snap action and to be disengaged from said set with a quick snap action; and means to prevent the engagement of said switch member with more than one of said sets at one time.

50 15. A device of the character described comprising a handle; a set of one or more terminal contacts; a switch member adapted to be electrically connected with a main circuit and controlled by said handle; means to operate said second switch member independently of said second handle to engage said second set of contacts with a quick snap action and to be disengaged from said set with a quick snap action; said switch members having operative connection such that movement of one to engage its set will, if the other switch is engaging its set, break the latter engagement before said one switch engages 55 its set.

60 16. A device of the character described comprising a handle; a set of one or more terminal contacts; a switch member adapted to be electrically connected with a main circuit and controlled by said handle; means to

operate said switch member independently of said handle to engage said set of contacts with a quick snap action and to be disengaged from said set with a quick snap action; a second handle; a second set of one or more terminal contacts; a second switch member adapted to be electrically connected with said main circuit and controlled by said second handle; means to operate said second switch member independently of said second handle to engage said second set of contacts with a quick snap action and to be disengaged from said second set of contacts with a quick snap action; and means to prevent the making of the connection between 70 both of said switch members and their respective sets of contacts at the same time.

16. A device of the character described comprising two sets of terminal contacts, each set comprising one or more of such contacts; a control member, a switch member adapted to be electrically connected to a main circuit; a spring directly connected to said control member and to said switch member and being put under stress by said control member and when so stressed causing said switch member to engage either one of said sets of contacts as desired with a quick snap action and to be disengaged from either one of said sets as desired with a quick snap action, 75 the path of movement of said switch member being unobstructed at all times.

17. A device of the character described comprising two sets of terminal contacts, each set comprising one or more of such contacts; a control member; a switch member adapted to be electrically connected to a main circuit; a spring directly connected to said control member and to said switch member and being put under stress by said control member and when so stressed causing said switch member to engage either one of said sets of contacts as desired with a quick snap action and to be disengaged from either one of said sets as desired with a quick snap action, 80 the path of movement of said switch member being unobstructed at all times and means to prevent the engagement of said switch member with more than one of said sets at one time.

18. A device of the character described comprising two sets of terminal contacts, each set comprising one or more of such contacts; a control member; a switch member adapted to be electrically connected to a main circuit; a spring directly connected to said switch member and being put under stress by said control member and when so stressed causing said switch member to engage either one of said sets of contacts as desired with a quick snap action and to be disengaged from either one of said sets as desired with a quick snap action, 85 the path of movement of said switch member being unobstructed at all times.

19. A device of the character described comprising two sets of terminal contacts, each set comprising one or more of such contacts; a control member; a switch member adapted to be electrically connected to a main circuit, a spring directly connected to said switch member and being put under stress by said control member and when so stressed causing said switch member to engage either one of said sets of contacts as desired with a quick snap action and to be disengaged from either one of said sets as desired with a quick snap action, the path of movement of said switch member being unobstructed at all times, and means to prevent the engagement of said switch member with more than one of said sets at one time.
20. A device of the character described comprising two sets of terminal contacts, each set comprising one or more of such contacts; a handle; a switch member adapted to be electrically connected to a main circuit; a spring directly connected to said handle and to said switch member, movement of the handle from either of its positions of rest putting said spring under compression, said spring at a predetermined point in the movement of the handle, expanding and operating the switch member independently of the handle to cause the switch member to have a quick snap action both in making and in breaking the circuit.
21. A device of the character described comprising two sets of terminal contacts, each set comprising one or more of such contacts; a pivoted handle; a pivoted switch member adapted to be electrically connected to a main circuit, the pivots of the handle and switch member being substantially coincident; and a spring directly connected to the handle and to the switch member, the point of connection of the switch member and spring being nearer to said pivots than the point of connection of the spring and handle, movement of the handle from either of its positions of rest putting said spring under compression, said spring acting at that time to hold said switch member in its make or break position, said spring, at a predetermined point in the movement of the handle expanding and operating the switch member independently of the handle to cause the switch member to have a quick snap action both in making and in breaking the circuit.
22. A device of the character described comprising two sets of terminal contacts, each set comprising one or more of such contacts; a handle; a switch member adapted to be electrically connected to a main circuit; a spring having one end directly connected to the switch member and the other directly to the handle, movement of the handle from either of its positions of rest bringing said ends nearer together and putting said spring under compression, said spring, at a predetermined point in the movement of the handle, expanding and operating the switch member independently of the handle to cause the switch member to have a quick snap action both in making and in breaking the circuit.
23. A device of the character described comprising two sets of terminal contacts, each set comprising one or more of such contacts; a handle; a switch member adapted to be electrically connected to a main circuit; a bow spring having one end connected directly to the switch member and the other directly to the handle, movement of the handle from either of its positions of rest bringing said ends nearer together and putting said spring under compression, said spring, at a predetermined point in the movement of the handle, expanding and twisting bodily to operate the switch member independently of the handle to cause the switch member to have a quick snap action both in making and in breaking the circuit.
24. A device of the character described comprising two sets of terminal contacts, each set comprising one or more of such contacts; a pivoted handle; a pivoted switch member adapted to be electrically connected to a main circuit, the pivots of the handle and switch member being substantially coincident; and a spring directly connected to the handle and to the switch member, the point of connection of the switch member and spring being nearer to said pivots than the point of connection of the spring and handle, said handle controlling said switch member through said spring but said spring operating said switch member independently of said handle with a quick make and a quick break, said switch member and handle having relatively opposite movements of rotation during the making movement and during the breaking movement.

HERMAN G. PAPE.
